UNITED STATES PATENT OFFICE.

JOHN A. HUGHSON, OF NEW YORK, N. Y.

FASTENER FOR SHIRTS, COATS, AND THE LIKE.

Application filed January 24, 1927. Serial No. 162,954.

The object of this invention is to provide a simple and economical construction for fastening the front openings of shirts, barbers' coats, and the like, without the employment of the buttons generally used for this purpose, and to so constitute the construction that when in place on the wearer, the presence of the invention will not be apparent.

In practically carrying out the present invention, for example, on a shirt, a series of loops are vertically spaced apart along one side of the opening in the front of the shirt. Along the other side of the opening are correspondingly spaced holes which, when the marginal edges of the opening are each brought into proper overlapped relation, are adapted to receive the corresponding loops. Secured to the upper portion of the shirt, preferably by sewing beneath the neckband is a tongue of sufficient length to reach downwardly to a point below the bottom loop and hole and after the loops have been drawn through the holes as described, the tongue is adapted to be passed downwardly through the several loops in succession.

The free end portion of the tongue is preferably of relatively stiff material so as to facilitate the threading of the tongue through the loops and said lower end portion is provided with a retaining finger adapted to overlie the lowermost loop and extend into a pocket formed in the tongue for the purpose of positively locking the tongue against inadvertent withdrawal. The side of the shirt front in which the openings are formed is further provided with a flap, the upper edge of which is sewed under the neckband of the shirt and one marginal edge of which flap is stitched down to the body of the shirt, so that in normal position, the flap will overlie and completely conceal the holes, loops and tongue, whereby the shirt will, to the casual observer, present the appearance of a conventional closed shirt front.

The invention is structurally simple and economical to manufacture, is thoroughly efficient, in its operation and entirely obviates the disadvantages universally recognized in the use of buttons.

Features of the invention, other than those specified, will be apparent from the herein-after detailed description and claims, when read in conjunction with the accompanying drawings.

The accompanying drawings illustrate one practical embodiment of the invention, but the construction shown therein is to be understood as illustrative, only, and not as defining the limits of the invention.

Figure 1 shows a shirt embodying the present invention with the parts of the fastener released and the front opened.

Figure 2 shows the shirt front closed and held in place by the fastening means of this invention.

Figure 3 is a section on the line 3—3 of Figure 2.

Figure 4 is a section on the line 4—4 of Figure 3; and,

Figure 5 is a fragmental perspective view taken partly in section on the line 5—5 of Figure 2.

The fastening means of this invention may be applied to the open front of a barber coat, union suit, or the like, but for the purpose of illustration, I have shown the invention as incorporated in shirt construction. Thus, in the drawings, 1 designates a shirt of the open front type. The respective side portions of the front of the shirt are designated 2 and 3, the neckband 4 and the collar button holes, common to shirt construction, are illustrated at 5.

Along the free edge 2^a of the front portion 2 and spaced a short distance from said edge are loops 6. These loops may be conveniently formed of tape, sewed upon the portion 2 in such manner as to extend forwardly 90 therefrom. Adjacent the edge 3^a of the shirt front portion 3 are formed a series of holes 7. These holes are of substantially the same size as the loops 6 and are similarly placed, so that when the front portions of the shirt are brought into cooperative relation with the collar button extending through the holes 5 and the portion 3 overlapping the portion 2, the loops 6 will register with the holes 7 and may be drawn through said holes. I may, if so desired, make the loops of relatively stiff material, so that they will possess more body or rigidity than the material from which the shirt is made in order to facilitate their insertion through the hole 7.

8 designates a tongue. This tongue is secured at its upper end to the shirt in a permanent manner. It may be sewed beneath the neckband 4 at the time the neckband is put on or, if desired, it may be sewed to the part 3 of the shirt somewhere down from

the neckband, but above the top opening 7. This tongue is of sufficient length to extend from this point of attachment downwardly to a point below the bottom hole 7, and is 5 of a width and texture to permit it to be readily threaded through the loops 6 after they have been passed thru the opening 7, as shown in Figure 2.

Here it will be noted that the tongue 8 extends downwardly through the several loops 6 in succession and projects below the lowermost loop. I find it convenient to form the lower end portion of the tongue in such manner as to make it relatively stiff. This 10 may be accomplished by using heavier material for the end portion of the tongue and by uniting such heavier material preferably formed in two or more plies to the remaining portion of the tongue after the manner shown in Figure 5.

In this latter figure, the relatively stiff end portion of the tongue is designated 8^a, while the remaining relatively flexible portion thereof is designated 8^b. These two 15 portions being united by stitching, as shown at 9.

At the free end of the tongue is sewed a locking finger 10, the stitching being designated at 11. The free end of this tongue 20 extends back along the tongue and its free end is adapted to be inserted through a slit 12 formed in the outer ply of the part 8^a. When the tongue is in the position shown in Figure 1, this locking finger 10 is withdrawn 25 from the slit 12 as shown in dotted lines in Figure 5, and while it is in this position, the tongue is passed through the several loops 6. After it has been passed through all of the loops, the finger is bent down over the 30 lowermost loop 6, and the end of the finger tucked into the slit 12, so as to positively lock the free end portion 8^a to said lowermost loop, and thus preclude inadvertent shifting of the tongue. When it is desired 35 to remove the tongue, the finger is withdrawn from the slit 12 and allowed to bend back, so that the tongue may be readily pulled upwardly through the several loops 6 to release said loops and allow of the opening 40 of the shirt.

In order that the parts, which I have described, may be concealed from view when the shirt is worn and the front closed as described, a flap 14 is mounted on the part 3 of the shirt, as shown in Figs. 1 and 2. The upper end of this flap extends under the neckband and one of the lateral edges is sewed down tightly to the portion 3 by one or more lines of stitching 15. This flap normally partakes of the position shown in 50 Figs. 2 to 5, inclusive and serves to cover and conceal the entire fastening means. The flap is shown as folded back to allow the fastening means to be seen. This, however, 55 is an abnormal position which the flap is

adapted to occupy only when the tongue is being inserted or removed from the loops.

The construction which I have described may be manufactured economically, and is thoroughly efficient for the carrying out of 70 its intended purposes. It is free from the well known objections incident to the use of buttons and positively precludes the opening of the shirt unless it is manually opened.

The foregoing detailed description sets 75 forth the invention in its preferred practical form, but the invention is to be understood as fully commensurate with the appended claims.

Having thus fully described the invention, what I claim as new and desire to secure by Letters Patent is:

1. A garment provided with an opening extending downwardly thereof, a series of loops secured to one side of the opening 80 in vertical spaced apart relation to one another, and adapted to extend through correspondingly positioned holes formed in the garment adjacent the opposite side of the opening, when said latter side of the opening is in overlapped relation with respect to the former side, a tongue permanently secured at its upper end to the overlapping side of the opening above the uppermost hole therein and which tongue is adapted 90 to be threaded downwardly through the several loops in succession after said loops have been passed through the holes, and a flap sewed to the overlapping side of the opening and adapted to normally overlie 100 the holes, loops and tongue for the purpose of covering and concealing the same.

2. A garment provided with an opening extending downwardly thereof, a series of loops secured to one side of the opening 105 in vertical spaced apart relation to one another, and adapted to extend through correspondingly positioned holes formed in the garment adjacent the opposite side of the opening, when said latter side of the opening is in overlapped relation with respect to the former side, a tongue permanently secured at its upper end to the overlapping side of the opening above the uppermost hole therein and which tongue is adapted to 110 be threaded downwardly through the several loops in succession after said loops have been passed through the holes, the free end portion of the flap being provided with means to engage with the lowermost loop for the 115 purpose of securing the tongue against inadvertent unthreading from said loop, and a flap sewed to the overlapping side of the opening and adapted to normally overlie the holes, loops and tongue for the purpose 120 of covering and concealing the same.

3. A garment provided with an opening extending downwardly thereof, a series of loops secured to one side of the opening in vertical spaced apart relation to one another, 130

and adapted to extend through correspondingly positioned holes formed in the garment adjacent the opposite side of the opening, when said latter side of the opening 5 is in overlapped relation with respect to the former side, a tongue permanently secured at its upper end to the overlapping side of the opening above the uppermost hole therein and which tongue is adapted to be threaded downwardly through the several 10 loops in succession after said loops have been passed through the holes, a locking finger mounted adjacent the free end of the tongue and adapted to be passed over the lowermost 15 loop and inserted into a pocket formed in the tongue to positively secure the free end of the tongue to said lowermost loop, and a flap sewed to the overlapping side of the opening and adapted to normally overlie the 20 holes, loops and tongue for the purpose of covering and concealing the same.

4. A garment provided with an opening extending downwardly thereof, a series of loops secured to one side of the opening in vertical spaced apart relation to one another, 25 and adapted to extend through correspond-

ingly positioned holes formed in the garment adjacent the opposite side of the opening, when said latter side of the opening is in overlapped relation with respect to the former side, a tongue permanently secured at its upper end to the overlapping side of the opening above the uppermost hole therein and which tongue is adapted to be threaded downwardly through the several 30 loops in succession after said loops have been passed through the holes, a locking finger mounted adjacent the free end of the tongue and adapted to be passed over the lowermost 35 loop and inserted into a pocket formed in the tongue to positively secure the free end of the tongue to said lowermost loop, and a flap sewed to the overlapping side of the opening and adapted to normally overlie the 40 holes, loops and tongue for the purpose of covering and concealing the same, the free end portion of said tongue being relatively stiff to facilitate the threading of the tongue through the loops.

In testimony whereof I have signed the 45 foregoing specification.

JOHN A. HUGHSON.
